CLAIM

The ornamental design for a portable cleaning station for physically disable patients, as shown and described.

DESCRIPTION

FIG. 1 is a top perspective view of a portable cleaning station for physically disable patients;

FIG. 2 is a bottom perspective view of thereof;

FIG. 3 is a top plan view thereof;

FIG. 4 is a bottom plan view thereof;

FIG. 5 is a left-side elevational view thereof;

FIG. 6 is a right-side elevational view thereof;

FIG. 7 is a front elevational view thereof; and,

FIG. 8 is a rear elevational view thereof.

The broken line showing in FIG. 1-8 is included for the purpose of showing environmental structure and forms no part of the claimed design.
